UNITED STATES PATENT OFFICE.

TORBJÖRN LINGA, OF WINTHROP HARBOR, ILLINOIS.

CARBURETER.

1,345,546.

Specification of Letters Patent.

Patented July 6, 1920.

Application filed June 29, 1916. Serial No. 106,575.

To all whom it may concern:

Be it known that I, TORBJÖRN LINGA, a subject of the King of Norway, residing at Winthrop Harbor, in the county of Lake and State of Illinois, have invented certain new and useful Improvements in Carbureters, of which the following is a specification.

One of the leading objects of the present invention is to provide a vaporizer or carbureter adapted to supply two or more fuels and equipped with automatic means to shift from one to another, such automatic means being under temperature control, preferably, the temperature of the vaporizer.

15 A further feature of the invention resides in subjecting the mixture of air and fuel to centrifugal action to repel the unvaporized portions of the mixture against a hot surface, preferably, one heated by the exhaust 20 from the engine, the construction desirably being such that this portion of the vaporizer acts as a trap which prevents the unvaporized liquid from passing on through the structure until it is completely gasified. The 25 air, however, is permitted to pass through the vaporizer practically unheated.

A still further characteristic of the invention resides in means for gradually switching from one fuel to another, which 30 may be accomplished either by hand or automatically under temperature control. Consequently, in a structure of this kind, where the engine is started on gasoline and run, for example, on a low grade fuel, such as 35 kerosene, distillate, naptha, solar oils, etc., there is a saving of gasoline by so constructing the device as to secure a slow, regular shifting from the one fuel to the other.

40 The improved device also desirably provides means for introducing water into the mixture after complete vaporization of the latter so that, in changing into steam in the engine cylinder, the latent heat will be employed for cooling the engine.

When the engine is throttled down and running without load, it does not require the supply of water, in fact, it needs the heat developed by the compression to favor 50 the ignition and in my improved construction the water-supply is automatically cut off by reason of the fact that the suction of the engine is reduced. In the preferred embodiment of the invention, the water nozzle 55 is above the water-supply level a sufficient amount so as to require a certain suction to

effect its injection into the mixture, and when such suction or partial vacuum is reduced on the throttling down of the engine, as referred to, it is insufficient to supply the 60 water but the suction is enough, however, under ordinary running unthrottled conditions to inject a definite percentage of water into the mixture.

Furthermore, owing to the difference in 65 specific gravity, viscosity, or sluggishness of the two fuels in action, in this novel device, the level of kerosene or other low-grade fuel is maintained slightly higher than that of the gasoline so as to offset this difference 70 in their inherent characteristics.

The vaporizer is also conveniently constructed so that as the throttle approaches its closed position there is an automatic increase in the percentage of gasoline fed and 75 a corresponding automatic decrease in the amount of kerosene or other heavier fuel.

The improved construction is so made that a single nozzle adjusts the feed for both fuels, and the proportion of the two fuels 80 during the normal running of the engine can be fixed; that is to say, it is not necessary to run on either fuel alone, but a definite fixed proportion between the two can be maintained, if desired.

These constitute some of the principal and salient features of the invention, but other novel advantages from the employment of this invention in a device of this character will become apparent to those skilled in the 90 art from the description of a preferred embodiment of the invention given below which should be taken in connection with the accompanying drawings illustrating such structure, and throughout the various views of 95 which like reference characters refer to the same parts.

In these drawings:

Figure 1 is an elevation of the vaporizer or carbureter;

Fig. 2 is a fragmentary view of the fuel-controlling valve-operating mechanism;

Fig. 3 is a plan view of the lower portion or bowl of the structure constituting the fuel and water reservoirs or compartments;

Fig. 4 is a vertical section on line 4—4 of Fig. 3;

Fig. 5 is a central vertical section through the appliance;

Fig. 6 is a horizontal section on line 6—6 110 of Fig. 5, and

Fig. 7 is a horizontal section on line 7—7

of Fig. 5 illustrating the circular thermostat and its coöperation with the fuel valves.

Referring to the drawings, it will be clear that the lower portion of the structure comprises a bowl 10 divided by three radiating walls 11, 12, and 13, (Fig. 3), and a co-operating centrally-disposed circular up-standing-wall 14 into three compartments or chambers 15, 16, and 17, of which the chamber 15 is adapted to contain a supply of kerosene, the receptacle 16 to hold a charge of water, and the compartment 17 to accommodate a supply of gasoline or other suitable liquid fuel.

As is illustrated in Figs. 2 and 3, the bowl inside of the rim 14 has a central passage 18 extended upwardly therethrough. Centrally arranged in such passage, an apertured boss 19 is located, forming part of a bracket 20 cast integral with the bowl-structure and projecting inwardly from the inner face of the circular rim 14. A pipe 21 is screwed into the lower portion of the aperture of boss 19 and on its lower end there is threaded an air intake member 22 open at 23 and provided with a centrally-threaded hub 24 screwed on the lower end of pipe 21 and connected to the depending flange or wall 22 by a web or plate part 25 provided with two circular concentric apertures 26 and 27, the part 25 being strengthened by a plurality of brackets 28 cast integral with the structure. Two ring-valves 29 and 30 of different weights and diameters are adapted to rest on the part 25, closing the circular apertures 26 and 27 as illustrated in Fig. 5. A sleeve 31 surrounds the pipe or tube 21 below the boss 19 and is provided with a plurality of feet 32 adapted to rest on the apertured plate 25 and also with curved arms 33 constituting valve guides and stops.

At its upper end the aperture through the boss 19 accommodates a fuel-nozzle 34 having a fuel-opening 35 in its side with which opening the tapered end of a needle-valve 36 co-operates, such valve being located in a horizontal cavity or passage 37 in an enlargement 38 of the wall 13. The protruding end of valve 36 is equipped with a turning handle 39, a portion of the valve-stem being threaded at 40 and co-operating with a threaded portion of the cavity 37 so that turning of the valve adjusts its needle point with reference to the fuel outlet or opening 35. As is shown in Figs. 2 and 3, the valve stem projects through a packing-nut or stuffing-box construction 40.

The floor or bottom wall of the kerosene or other relatively heavy liquid fuel chamber 15 is provided with an internally-threaded boss 41 into which a pipe 42 is threaded, the latter having on one side a discharge opening 43 as illustrated in Fig. 4. Beneath the boss 41 the bowl is fitted for the reception of a kerosene inlet pipe 44 above which

a horizontal partition wall 45 is located, having a tapered centrally-disposed valve-opening 46 with which the lower conical end of the reduced portion 47 of a valve 48 co-operates. This valve is of substantially the same diameter as the interior of tube 42 and by its rising and falling movements is adapted to open and close the passage 43, as well as control the passage of the liquid through the valve-opening 46. A cork or other similar float 49 is mounted on an arm 50 which is fulcrumed at 51 to the spaced arms 52 and 53 rising from a nut 54 screw-threaded on the upper end of pipe 42 and held in place by a set-nut 55. Beyond its pivotal support the arm or lever 50 has a pair of spaced fingers 56, the ends of which are accommodated between two spaced enlargements 57 and 58 on the upper portion of valve-rod 48. It should be apparent from this construction that the float 49 controls the valve 46, 47, and maintains a definite level of kerosene or other similar liquid fuel in the compartment 15.

The chamber 17 is supplied with a float 59 controlling an inlet valve 60 governing the flow of gasoline or other relatively highly volatile fuel through the pipe 61 into the chamber, the construction in this instance being the same as that in connection with the kerosene compartment 15 except that the level of kerosene is maintained slightly higher than that of the gasoline, as illustrated by the positions of the floats in Fig. 4, to offset their slight differences in viscosity or sluggishness in action.

The kerosene chamber wall is thickened at 62 and is vertically apertured at 63 for the accommodation of a kerosene needle valve 64 and its surrounding spring 65 bearing at its lower end against a shoulder 66 on the valve. The lower conical end of the valve is adapted to close and establish communication between the kerosene compartment 15 and an inclined passage 67 connecting the lower-portion of such compartment with the opening 35, as shown in Fig. 5. In similar manner, communication between the gasoline chamber 17 and another inclined passage 68 connecting with the aperture 35 and with the bottom of the chamber is governed by the action of another spring-pressed needle valve 69, the downward pressure of whose spring is somewhat greater than that of the corresponding kerosene valve.

A horizontal flange 70 of the vaporizer is adapted to fit over the top of the bowl and is secured in place by a plurality of screws 71, 72, 73, and 74, taking into threaded cavities 75, 76, 77, and 78, respectively, of the bowl or member 10. The pair of screws 73 and 74 also secure to the top of the flange 70 the base of a bracket 79 on which a rocker 80 is fulcrumed at 81, such rocker having

below its fulcrum a curved foot, one end 82 of which is positioned beneath a nut 83 on the kerosene valve 64, the other foot 84 being located beneath a nut 85 on the 5 gasoline valve 69. Such rocker has a rearwardly or inwardly extended arm 86, (Fig. 7), which projects through an opening 87 in an annular shell 88 angularly adjustably fastened to the flange 70 by means of a screw 89 associated with the flange and extending through a curved slot 90 of an ear 91 forming part of the shell or band.

10 A round or circular thermostat 93, composed of two bars 93^a and 93^b, is accommodated within the band or shell 88 and the two metal bars are fastened to the band near one end by a screw 92, the other ends of such bars being in coöperative relation with the finger 86. The inner bar 93^b has a 20 somewhat greater coefficient of expansion than the outer bar 93^a so that when the thermostat is heated it tends to expand and straighten out, that is, its free end tends to travel toward the right as the parts are 25 viewed in Fig. 7, and, in order to permit a certain degree of this straightening action under heat the thermostat is loosely accommodated in the shell 88, that is to say, it does not form a tight fit therein.

30 Flange 70 has integral therewith and centrally arranged with respect thereto a hollow pipe or tube 94 with the opposite openings 95 and 96 in its cylindrical wall, the tube being divided into two non-communicating parts by an inclined baffle or division-wall 97.

A heating member having an inner tube 98 and an outer shell 99 provided with apertured, threaded, oppositely-disposed bosses 40 100 and 101 has a bottom portion 102 of reduced diameter resting on the flange 70 and received inside of the thermostat, this member being held properly in position by a circular part 103 fitting in the lower open 45 end of tube 98. This heating member is held down in position by a nut 104 having threaded engagement with the pipe or tube 94 and bearing against the upper end of the part 98. The two bosses 100 and 101 are adapted 50 to have pipes 105 and 106 screwed therethrough which the heated exhaust gases from the engine are adapted to pass, and, in order that the tube 98 may be effectively heated by such gas, it is provided with a 55 number of out-standing circular ribs or rings 107.

In the upper portion of the tube 94 a 60 throttle 108 is mounted on a shaft 109 having bearings in the tube-wall. An operating-arm 110 is angularly adjustably mounted on the shaft and another arm 111 is fixed to the shaft and carries an adjustable stop-screw 112 adapted to engage the nut or threaded collar 104 to limit the turning of 65 the shaft. This arm 111, by means of a bent

rod 113, constituting a connecting-link, is operatively associated with an arm 114 of the rocker 80, the rod extending downwardly through an aperture 115 of the arm and having mounted thereon an adjustable 70 abutment 116 which may be held frictionally in position and adjusted lengthwise the rod.

The springs 65 surrounding the kerosene and gasoline valves 64 and 69 respectively, bear at their upper ends against the bottom 75 face of the base of bracket 79, and, as has been indicated, they are of somewhat different strengths or capacities, that is to say, the spring for the gasoline valve is slightly stronger than that of the kerosene valve, 80 and, consequently holds the arm 86 in engagement with the end of the thermostat and tends to close the gasoline supply and open the kerosene supply.

In order to adjust the relative percentages 85 of the two fuels in the normal operation of the vaporizer, I provide the bracket 79 with a plurality of holes into any one of which a stop screw 117 may be placed, projecting sufficiently through the bracket for coöperation 90 with the pointer or arm 118 of the rocker.

The water compartment or chamber 16 is provided with an inlet valve 119 controlled by a cork float 120, which parts in construction are substantially like the corresponding instrumentalities associated with the receptacles 15 and 17. The rib 12 has an inclined enlargement 121 with a central passage 122 in communication near its lower 100 end through aperture 121^a with the water chamber 16 and receiving a needle valve 123 co-acting with the smaller nozzle 124 which communicates with and is in register with an opening 125, (Fig. 5), through the boss 105 103 outside of the baffle wall 97. The protruding end of such water valve 123 is supplied with an actuating-handle 126, a portion of the valve being threaded and coacting with a threaded part 127 of the passage 110 122, the valve extending through a stuffing-box construction 128, as will be readily understood. It will be apparent, therefore, that the nozzle or outlet 125 of this water chamber is located some distance 115 above the level of the water in chamber 16, which, of course, means that a definite degree of suction or vacuum must be exerted at the nozzle before the stream of water will 120 be lifted and discharged through the passage into the mixture of gases.

Operation: The operation of this appliance is practically as follows:

Let us assume that the compartment 17 has its supply of gasoline or other similar 125 fuel maintained at the proper level by the float control 59, that the chamber 15 has a similar supply of kerosene or other heavier fuel maintained at a higher level by its float 49, that the reservoir 16 contains a body of 130

water kept at the predetermined height by its float control, that the vaporizer is cold, and that it is desired to start the internal combustion engine with which the appliance 5 is associated. Let it be further understood that the engine is to start on gasoline alone, and, under normal running is to operate on kerosene solely, with, of course, the associated water. Under this cold inoperative 10 condition of the vaporizer, owing to the greater strength of the spring associated with the gasoline valve 69, and, since the thermostat is cold and contracted, the valve 69 will be in open position by reason of the 15 engagement of the thermostat with the arm 86 of the rocker, the kerosene valve 64 will be closed, and the rocker foot will be in a correspondingly inclined position. Stated differently, owing to the unbalanced action 20 of the springs associated with the two valves 64 and 69, the spring of the latter tends to close the gasoline valve but is prevented from doing so by the thermostat which holds the rocker in such inclined position that 25 the gasoline valve will be open and the kerosene valve closed.

When the throttle 108 and the needle valve 36 are open and the engine with which the vaporizer is associated is started, the air 30 passing upwardly through the tube 21 entrains a certain amount of gasoline, extra air entering the device through the passages 26 and 27 or possibly the passage 26 alone, depending upon the degree of suction exerted. The mixed air and gasoline enter the tube 94 below the inclined division-wall or baffle-plate 97 and pass out through the hole 96 into the space between the tube 94 and the inclosing tube 98. This mixture 35 passes part way around the tube 94, enters the tube again through the opening 95 above the baffle-plate, and passes on upwardly past the throttle to the engine. We may also assume that the valve 123 is open and, 40 whether or not any water is discharged through the nozzle 125 and becomes admixed with the mixture above the baffle-plate will depend upon the degree of suction or vacuum exerted. The exhaust from the engine 45 passing through the pipes 105 and 106 gradually heats the tube 98 and also the thermostat 93, causing a gradual straightening of the latter which results in a rocking of the member 80 in a clockwise direction 50 under the action of the stronger gasoline spring gradually shutting off wholly or in part the feed of gasoline to the mixture and slowly and regularly increasing the supply of kerosene or other similar fuel in 55 the compartment 15 to the valve opening 35. Under normal running of the engine, the parts may be so adjusted that the gasoline will be entirely cut off and the engine 60 run solely on kerosene. By limiting the 65 movement of the rocker 80 by the introduc-

tion of the screw 117 into one of the holes of the bracket 79, predetermined percentages of combined gasoline and kerosene may be fed to the engine under ordinary running conditions. That is to say, the presence of 70 such stop screw limits the closing of the gasoline valve and, consequently, the extent of opening of the kerosene valve.

It should be noticed that the mixture in passing out through the opening 96 and 75 through the curved space between the pipe 97 and the casing 98, and then into the opening 95 repels the liquid particles in the mixture against the heated inner surface of the wall 98 under the action of centrifugal 80 force, and that this construction acts somewhat as a trap to prevent such liquid particles from passing on with the mixture until they are completely vaporized. The air, of course, takes an inner course, being of less 85 density than the liquid particles and it is not so much subjected to the action of the heat of shell 98.

It should be observed also that the stream of water discharged through the nozzle 125 90 does not pass through the passage between the parts 96 and 98 and is not subjected to the heat of the latter, but becomes admixed with the gaseous mixture after the latter again enters pipe 94 above the baffle 95 wall or partition 97. The introduction of this water into the engine keeps the compression temperature down by reason of the latent heat absorbed by the water as it becomes changed into steam. The presence of 100 this water also maintains the temperature in the engine at a point below that at which kerosene or similar fuel is likely to pre-ignite. In addition, it also keeps the temperature below that at which the kerosene 105 would decompose and tend to deposit carbon. Furthermore, the water vapor or steam combines with the carbon or hydrocarbons of the mixture to produce certain combustible gases which would not be present if air 110 alone were used. When, however, the engine is throttled down and running without load, it requires the heat of the fuel to maintain a proper temperature for ignition, and the presence of water under such circumstances would be detrimental. The construction of the device is such that the nozzle 125 is located above the water level in compartment 16 a sufficient distance so that the water will be discharged into the mixture 115 120 only when the throttle is opened a substantial amount, and when it is closed more than this, the suction exerted on the water is insufficient to raise a column for discharge through the nozzle into the mixture. This 125 result is accomplished, as will be appreciated, by locating the discharge nozzle 124 or 125 a distance above the level of the water in chamber 16.

In some cases, as the throttle is closed 130

more or less, it is desirable to increase the percentage of gasoline, and this is effected in the device described by the connection 113, which opens the gasoline valve and 5 closes the kerosene valve somewhat as the throttle approaches its closed position. This, of course, is effected automatically by reason of the structural elements employed and their interconnection with one another, 10 as has been explained. Such movement of the rocker and the associated valves is effected against the action of the valve springs and may move the arm 86 of the rocker away from the end of the thermostat.

15 When the throttle is closed and the engine stopped the vaporizer, of course, cools, the thermostat contracts, and the gasoline and kerosene control valves automatically assume their original positions under the influence of the thermostat acting in opposition to the valve springs. That is to say, 20 the gasoline valve will be opened and the kerosene valve closed.

By this arrangement of structural elements, the usual priming and switching is 25 avoided and the amount of gasoline required for starting the engine is reduced to a minimum because of the almost immediate commencement of closing of the gasoline needle valve and the simultaneous opening of the heavier fuel needle valve. It should be observed that the two valves 64 and 69 merely determine the proportions of 30 the two ingredients and that the fuel adjustment is effected solely by the fuel needle valve 36 which, of course, controls the passage of the mixture to the vaporizer.

Attention is also summoned to the fact that this vaporizer or carburetor operates 40 on the principle of separating all of the liquid fuel particles from the air and subjecting them to a high degree of heat by reason of their contact with the heated wall 98, the air, however, being permitted to 45 pass through the vaporizer largely unheated.

The above description of the automatic regulating of the feed of water is based 50 upon the assumption that the vaporizer is associated with an engine the governing of which is effected by throttling. The vaporizer is equally automatic and effective in operation when connected to an engine controlled on the "hit and miss" plan. When 55 such an engine is running idle the suction exerted corresponding to the intake of each explosive charge is of the normal force or amount, and, of course, there is no suction on the vaporizer for the omitted explosions. 60 The device could, therefore, automatically reduce the amount of water fed to each charge and the amount fed should be proportioned to the frequency of the explosions. This is automatically accomplished 65 in this improved appliance.

Referring to Fig. 5, it will be clear that there is a certain volume or chamber in the water passage between valve 123 and nozzle 125 which may equal or exceed the amount of water the mixture should receive for 70 each charge when the engine is running at full load. Under such full load there is only a slight leakage past valve 123 into the water chamber 16 so that each mixture charge will receive its full quota of water. 75 If, however, the engine is running idle with infrequent explosions and many cut-outs, a much greater return of such water past the valve occurs so that each explosive mixture charge will receive a lesser amount of water, 80 which, of course, is what is desired under such circumstances. For intermediate loads, the amount of water fed will be proportioned to the load for the reason indicated. Stated differently, the construction 85 is of the nature of a suction pump with a leaky check-valve, the efficiency of which pump increases with the frequency of its strokes, that is, the frequency of the explosions. 90

While I have herein set forth in detail one desirable embodiment of the invention, it is to be understood that the invention is not limited and restricted to the precise and exact structural features presented, because 95 many minor mechanical changes may be made in the structure without departure from the invention and without the sacrifice of any of its substantial benefits and advantages. 100

I claim:

1. A carburetor of the character described, including in combination, compartments for a plurality of fuels of different specific gravities connected by separate passages to a nozzle communicating with the mixing chamber of the carburetor, an adjustable needle-valve for said nozzle, float-controlled valves preserving predetermined liquid fuel levels in said compartments, 105 valves controlling said passages between said compartments and nozzle, uniting means associated with said passage valves controlling the flow ratio of the fuels from said compartments to the mixing chamber 110 through the nozzle, a throttle, and means connecting said throttle and uniting means whereby the fuel ratio delivered to the nozzle may be determined by the position 115 of the throttle, substantially as described. 120

2. A carburetor of the character described, including in combination, compartments for a plurality of fuels of different specific gravities connected by separate passages to a nozzle communicating with the mixing chamber of the carburetor, an adjustable needle-valve for said nozzle, float-controlled valves preserving predetermined liquid fuel levels in said compartments, 125 valves controlling said passages between 130

said compartments and nozzle, uniting means associated with said passage valves controlling the flow ratio of the fuels from said compartments to the mixing chamber 5 through the nozzle, a thermostat associated with and adapted to actuate said uniting means, a throttle, and means connecting said throttle and uniting means whereby the

fuel ratio delivered to the nozzle may be determined by the position of the throttle, 10 substantially as described.

TORBJÖRN LINGA.
